UNITED STATES PATENT OFFICE

MAURICE F. PHILLIPS, OF RICHMOND, VIRGINIA

OUTDOOR ADVERTISING DEVICE

Application filed October 19, 1928. Serial No. 313,522.

The present invention relates to improvements in outdoor advertising devices, one object thereof being the provision of a movable sign arrangement in which signs or cards bearing advertising or similar matter are successively presented to view in appearing and disappearing relation so as to attract the attention of the public.

Another object of the invention is the provision of an outdoor sign apparatus in which a casing provided with a sign presentation aperture is so combined with the sign delivery mechanism that signs are presented in interrupted succession, that is, one sign is moved forward into presentation position and moved backward therefrom before the next sign is brought into view, the projecting and retracting positions of the sign being in substantially the same plane, so that the advertising matter carried thereby is presented to view during the complete action.

With the foregoing and other objects in view, which will appear as the description proceeds, the invention resides in the combination and arrangements of parts and in the details of construction hereinafter described and claimed, it being understood that changes in the precise embodiment of the invention herein disclosed can be made within the scope 30 of what is claimed without departing from the spirit of the invention.

In the drawings:—

Figure 1 is a perspective view of the complete apparatus.

Figure 2 is a longitudinal sectional view therethrough.

Figure 3 is a section on line 3—3 of Figure 2.

Figure 4 is an enlarged detail sectional view of one of the sign holding racks and the adjacent portion of the sign mounted thereon or a section on line 4—4 of Figure 2.

Figures 5 and 6 are detail views in side elevation and top plan of one form of endless belt or chain and sign-carrying member.

Referring to the drawings, the numeral 7 designates a substantially rectangular casing which is here shown as mounted upon pedestals 8, said casing being provided with a rectangular opening 9 at the front wall thereof

and said opening being normally closed by a transparent sheet of glass 10. Mounted within the cabinet at opposite sides of the opening 9 and projecting rearwardly therein are the two parallel wings 11, and disposed above and below the opening within the cabinet are the illuminating lamps 12.

Mounted within the cabinet at the rear thereof is a motor or prime mover M, which is preferably an electric motor, the same driving a bevel gear or pinion 13 which is in mesh with the bevel pinion 14 keyed upon the shaft 15. This shaft is properly journaled within the cabinet and carries two sprocket wheels 16 and 16' which, in turn, operate through the chains 17 and 17' the two short shafts 18—18', said shafts, as clearly shown, being provided with sprockets 19 and 19' over which are trained the sign conveying chains 20 and 20'. Thus, the shaft 15 will drive the conveyor chains which are properly trained, as will presently appear, to perform the desired function. Mounted upon each side of the cabinet to guide the respective chains are the sprockets 21, 22 and 23, as clearly shown in Figure 2, and the chain is caused by the motor to travel in the direction of the arrows, as indicated in Figure 2, so that the arms 24, (Figs. 5 and 6) carried by the chains 20 and 20' and which carry the sign-engaging hooks 24' are positioned to properly engage and release the signs, as will presently appear. Mounted within the cabinet and secured to the opposite side walls thereof, as shown in Figure 4, are brackets 25 which, in turn, support the rails or rods 26 in an inclined position, the forward end of each rail being provided with a hooked end 27 to successively receive and support curved supporting arms 30 extending laterally from the signs 28 at or adjacent the upper edges of the latter.

Each sign 28, as here shown, is provided on its rear face with spacing members 29 to properly space the same from the next succeeding sign, as illustrated in Figure 2, and in the proper position upon the racks 26, the incline of the rack being such as to deliver the signs forwardly by gravity after they have been 100

placed thereon through the intermediary of the endless conveyors.

It will thus be seen that when the conveyor chains 20 and 20' are moving in the direction of the arrow (Figure 2), the hooks 24', which are spaced in proper relative position so that the signs will not interfere with one another in moving into exhibiting and non-exhibiting position, will be inserted in the curved arms 30 at the upper corners of each sign in such a manner that the sign will be lifted from the hooks 27 of the rails 26 and will assume the dotted line position shown in the lower portion of Figure 2. As soon as the sign has passed the sprockets 21 and 21', it enters between the wings 11 and moves in a horizontal plane toward the opening 9 and until it passes under the sprockets 22 and 22', at which time, the hooks 24' are carried around the sprockets 20 and the sign is bodily elevated and moved rearwardly, assuming the dotted line position shown in the upper portion of Figure 2 with the lower edge thereof slightly above the position it assumes when moving toward the opening 9. Thus the sign will be moved forwardly toward the opening 9 and then rearwardly in a slightly elevated position between the wings 11, and, when the sign has reached the position, as shown in broken lines in the upper part of Figure 2, the next succeeding new sign is elevated and started on its way toward presentation position without interference by the sign which has been previously exhibited. As the sign continues rearwardly and passes downwardly past the sprockets 23 and 23', the curved arms 30 thereof are engaged by the rearwardly projecting ends of the rails or racks 26 and deposited thereon and disengaged from the hooks 24' of the chains 20 and 20', said hooks 24' continuing in a downward direction and moving past the sprockets 19 and 19' to again pick up the sign which at that time is supported by the hooked ends 27 of the rods 26. Although the portions of the chains 20 and 20' between the sprockets 19, 19' and 21, 21' have been illustrated at such an angle as to cause an interval of time between the presentation of one sign and the presentation of the next sign at the opening 9, it is possible to locate the sprockets 19, 19' and 20, 20' closer together, thus causing the chains to travel at a steeper angle between said sprockets so that the signs will be presented at the opening 9 without a prolonged intermission, as here illustrated.

From the foregoing description, it will be evident that in presenting a sign to view, or displaying it in the exhibiting position, the sign is carried forwardly with its upper edge in the same horizontal plane and then rearwardly with its upper edge slightly elevated, the signs being suspended in vertical position so as to properly present the advertising matter carried thereby through the opening 9 to

attract the attention of the public due to the forward and rearward movement of the sign.

I claim:—

1. A sign display device including a casing having a display opening, a plurality of signs normally supported in said casing and movable successively forwardly thereof, spaced endless sign conveyors in the casing, means for moving said conveyors in unison, means below and means above and rearwardly of said opening over which stretches of said conveyors travel at an inclination toward said opening, means above said opening and adjacent thereto over which substantially parallel stretches of said conveyors travel toward and away from said opening, and means carried by the conveyors for engaging one sign at a time and carrying the same to and from said display opening. 70

2. A sign display device including a casing having a display opening, conveyors in the casing, means for causing said conveyors to move upwardly and then substantially horizontally forwardly toward said opening and then substantially horizontally rearwardly away from said opening, and means carried by the conveyors for engaging one sign at a time and carrying the same to and from said display opening whereby the sign is conveyed in the same position forwardly and then rearwardly before disappearing from view in the opening. 90

3. A sign display device including a casing having a display opening, sign-supporting means mounted in the rear portion of said casing, spaced endless sign conveyors movable in said casing and having a stretch movable upwardly at an incline toward said opening and stretches moving substantially horizontally in parallelism toward and away from said opening, a plurality of signs normally resting on said supporting means, and cooperating means carried by the conveyors and the signs whereby one sign at a time is picked up by the conveyor and moved toward and away from the display opening and then restored to said supporting means. 100

4. A sign display device including a casing having a display opening, a sign rack mounted in the rear portion of said casing, a prime mover mounted in said casing, two spaced endless sign conveyors operably actuated in unison by said prime mover, a plurality of signs normally supported by the rack, cooperating means carried by the conveyors and the signs whereby one sign at a time is picked up by the conveyors from the rack and moved toward the display opening and restored to the rear end of the rack after being displayed, the forward portions of said conveyors adjacent the display opening being movable in parallel spaced relation to cause the sign to be moved toward the opening in a straight line position and to be slightly elevated and moved in the opposite direction in 115

120

the same position, and a pair of wings carried by the cabinet at opposite sides of the opening and forming a shielded compartment between which the signs are moved when in
5 exhibiting position.

In testimony whereof I have hereunto set my hand.

MAURICE F. PHILLIPS.
